UNITED STATES PATENT OFFICE.

JOHN F. A. HOORT, OF NEW YORK, N. Y.

DESIGN FOR A MANTEL.

SPECIFICATION forming part of Design No. 24,136, dated March 19, 1895.

Application filed January 10, 1895. Serial No. 534,494. Term of patent 3½ years.

To all whom it may concern:

Be it known that I, JOHN F. A. HOORT, a citizen of the United States, residing at New York, in the county of New York and State of New York, have invented and produced a new and original Design for Mantels; and I do hereby declare the following to be a full, clear, and exact description of the same, reference being had to the accompanying drawing, forming a part thereof.

The figure of the drawing is an isometric view of the mantel.

The leading feature of my design consists in the design for mantels provided with supporting columns having rectangular pedestals and fluted cylindrical shafts and supporting an entablature surmounted by a shelf.

Numeral 1 denotes the mantel shelf which resembles an entablature of the Ionic order supported by columns 2 of the same order.

3, 3, denote the pedestals of the columns. These have considerable height as compared with the shafts 4, 4, and impart to the columns a pleasing effect. The lower part of each shaft is plain and its upper portion is fluted.

The neck 5 is made long as shown and ornamented by a rosette supporting festoons.

6 denotes a panel bounded above by the entablature and at each end by the upper portions of the columns and having on its lower edge a beading 7. The panel is ornamented by two rosettes 8 which together with vines appear to support festoons of flowers and foliage and an oval wreath. This panel ornament is surmounted by the said vines extending horizontally across the mantel arches formed by the festoons and arranged in crenelated form.

10 represents a back ground which at 11 extends above the mantel shelf and is provided with a crenelated molding 11.

What I claim is—

The design for a mantel as shown and described.

In testimony whereof I affix my signature in presence of two witnesses.

JOHN F. A. HOORT.
